UNITED STATES PATENT OFFICE.

HOMER ARTHUR KING, OF COLTON, CALIFORNIA.

ROTARY ENGINE.

No. 874,684.

Specification of Letters Patent.

Patented Dec. 24, 1907.

Application filed October 15, 1906. Serial No. 339,108.

To all whom it may concern:

Be it known that I, HOMER ARTHUR KING, a citizen of the United States, residing at Colton, in the county of San Bernardino and 5 State of California, have invented a new and useful Automatic Rotary Engine, of which the following is a specification.

My invention relates to improvements in automatic rotary engines, and the object of 10 my improvement is, first, to secure the most simple manner of uniting two or more engines on one revolving shaft, and avoid friction as much as possible by forming a motive-fluid chest just within the periphery between 15 two engines so that the pressure of the motive-fluid in said chest shall be equal on the edge or edges of the revolving valve or valves instead of on one side, one motive-fluid chest serving two engines, imparting 20 power to each alternately and by expansion giving continuous pressure on two or more piston heads; second, to construct the reversers or regulators so as to admit the insertion of oil pipes; third, to provide mechanism 25 for working the oscillating cylinder-heads automatically from and close to the revolving shaft, with a casing inclosing all of the mechanism except the sprocket wheel on the shaft and the crank that reverses the 30 engine; fourth, to prevent the escape of motive-fluid by inserts or packings on either or both below and above the motive-fluid chest, and on each side of the piston disk, near the periphery, resting against springs; fifth, to 35 further prevent escape of motive-fluid from the annular cylinder, when its construction is rectangular in cross-section, by employing rectangular collar rings with overlapping halved joints, resting against springs; sixth, 40 when the power is secured by the explosion of the motive-fluid, to provide chambers in the annular cylinder between each piston head and closed cylinder-head, the explosion being effected by means of a battery or lamp 45 as soon as the chambers are filled with condensed motive-fluid. I attain these objects by mechanism illustrated in the accompanying drawings, forming a part of this specification, in which—

50 Figure 1 is a cross section showing the union of two engines, Fig. 2 is a view of one side of my engine showing the mechanism for working the oscillating cylinder-heads when the engine is running in either direction, 55 and Fig. 3 shows the same mechanism used on the opposite side when two engines are

united; Fig. 4 is a cross sectional view of two engines united showing the rectangular form of the annular cylinders; Fig. 5 is an elevation of the reverser with oil pipe; Fig. 6 is an elevation of the regulator, two being used when two engines are united; Fig. 7 is an elevation of the revolving valve, preferably two being used and when two engines are united a little space being left between them 60 to prevent too much friction, the two being united by the packing disk K' and both secured to the disk by projections into slots permitting each valve to be gently pressed against its companion regulator L² by the 65 motive-fluid, and by a few coiled springs which may assist in pressing the valves apart; Fig. 8 shows packing ring K, although this ring may not be necessary; Fig. 9 is an elevation of disks C with piston heads E E 70 bolted thereto; Fig. 10 is a section of Figs. 1 and 4 taken on line t t of Fig. 1, showing the oscillating cylinder-heads F F turned down after piston heads E E have just passed; Fig. 11 is a cross section of a portion of the 75 disk C shown in Figs. 9 and 10, taken on line u u of Fig. 9, and showing only one of the spliced collar rings V of a piston head with springs W and packing rings K³ pressed outward by springs X; Fig. 12 is one of the disk 80 rings K³; Fig. 13 is portion of Fig. 4 but without reversers L³ L³ and regulators L² L²; and Fig. 14 is an elevation of one side of Fig. 13, 85 showing rods Z, Z, instead of the belt and chain connection shown in Figs. 2 and 3; 90 and showing also buffers Z² Z² arranged to strike rubber or air cushions Z' Z' causing cylinder-heads F F, to gently cease oscillating just at the right time.

A and B are the main parts of the annular 95 cylinder which may be formed circular with a milling machine and united as in Figs. 1, 2, and 3, or may be formed by a lathe taking a rectangular piston-head like Fig. 11 and united around the periphery like Figs. 4 100 and 10.

B' is one of the round removable portions of the annular cylinder furnishing access to the oscillating cylinder-heads F, and A' is the corresponding removable portion for the 105 other cylinder-head of the annular cylinder shown in Figs. 1, 2, and 3.

C is the piston head disk, there being two in each of the two double engines shown in this application.

D is the revolving shaft, D' is one of the sprocket-wheels and D² one of the two-armed

cam devices for actuating the pulley system controlling the movement of the cylinder-heads.

5 E is one of the piston-heads wider at the base to economize motive-fluid, and is bolted to the disk C which is splined to the shaft D.

F is one of the oscillating cylinder-heads, its periphery being circular in cross section for cylinders such as illustrated in Figs. 1, 2, 10 and 3, but straight for those of rectangular form like Figs. 4 and 10.

F' F' are buffers for the oscillating cylinder-heads, preferably air cushions, and are moved 90 degrees when actuated by the reversers L³ L³.

G is the cover for the pulley system actuating the cylinder-heads and may be easily removed.

H is an exhaust: I I are inlet ports for the motive-fluid when the engine is running forward, and I² I² are inlet ports for running backward as shown in Fig. 10. Chambers M' M' are for the motive-fluid and are made much larger when the power is obtained from the explosion of motive-fluid, the chambers M' M' being filled with compressed motive-fluid and I I or I² I² closed by the regulator and revolving valve while piston-head E is passing the cylinder-head F.

30 J is a chain, belt, or flexible connection secured to or passing one or more times around pulleys J' J', J² and J³ and operates cylinder-heads F F from close to the shaft by timely contact of the points or lugs of cams D² 35 against the small wheels J⁴ J⁵ or J⁶ J⁶ constituting operating pins or studs for one of the two united engines, these being operated on one engine while the other engine is running by expansion. Other forms and arrangements of cam and wheels or other methods 40 of operating the cylinder-heads might be used. The two lugs, on cams D², in revolving move studs J⁴ and J⁵, thus moving pulleys J² and J³ just enough in opposite directions to open and close the passage under 45 two oscillating cylinder-heads by means of sprocket chain J and pulleys J' J' to let piston-heads E E pass. When the reversers L³ L³ are moved to reverse the engine, the

50 connections S S shift the chain J, pulleys J' J' and J² J³, and bring studs J⁶ and J⁷ in position to contact with cams on D² instead of pins J⁴ J⁵, thus oscillating the cylinder-heads F F as before, but the piston-heads E E will then 55 be moving the engine in the reverse direction.

K is a packing-ring between the parts of the engine casing.

K² are packing-rings in the side or edge of 60 the piston head disk C which are pressed outward by the coiled springs.

x' are bent flat springs on the periphery of the valves L, serving to spread them apart.

A motive - fluid chest or opening I³ is 65 formed between the periphery of the revolv-

ing valves L L and the peripheral walls of the annular cylinder. Valves L L move with the supporting disk K', being prevented from turning thereon by set-screw stays N, the nuts thereon serving also to adjust the position of the valves. The valves L L are free to be forced apart by the motive-fluid and are also kept close to the regulators L² by means of coiled springs seated in shallow holes P P in the sides of the valves. The position of the reversers L³ is changed, for the purpose of reversing the engine, by means of the crank levers L⁵ and this movement also changes the position of the buffers F' F' correspondingly, as the buffers are connected to the reversers by means of springs S S.

In case the motive-fluid is used explosively, lamps or batteries are placed in cavities M M, which serve to explode the motive-fluid in the chambers M' M', as they pass the channels or openings leading to said cavities M M, the openings being closed so quickly that the light in the protected lamps is not extinguished.

Oil is conveyed to the bearings on the shaft D, through the tubes O. The usual circular collar rings are used on piston heads in Fig. 1 but in the construction shown in Figs. 4, 9, 10, 11, and 13, the collar rings U are rectangular, spliced or lapped at V V and are pressed outward by springs W. X is a coiled spring pressing the packing rings K K against the sides of the annular cylinder.

In Fig. 13, I have shown the engine without using the regulator L² and the reverser L³. 100 A removable part of the casing Y, affords easy access to the valve L, which may be adjusted by means of the block and set-screw N; when, however, the regulator L² and reverser L³ are used, openings may be provided each 105 side of the packing-ring K, to give access to a set-screw on the periphery of the valve, while the opening to admit motive-fluid to the chest I³ may be provided on either side of the packing-ring.

The general operation of my engine is as follows: Upon admitting the motive-fluid at high pressure into the chest I³, the fluid enters through inlets I² I², as shown in Fig. 10, into the chambers M' M' in cylinder-heads F F, 115 and propels piston-heads E E in the direction of the arrow, at first by direct pressure which is then cut off by the revolving valve L, the pistons E E then continuing under the expansion of the motive-fluid: Before exhausts H H are reached, however, the motive-fluid enters the other engine at two points, and thus continuous pressure is had on two or more piston-heads, avoiding dead points, and securing double leverage constantly.

When the engines are constructed like Fig. 13 without the reverser L³ or regulator L², a very long stroke is secured and the exhaust occurs only before the piston-heads reach the rising cylinder heads; with the reverser and 130

regulator on each side of the valves L L the stroke is not so long, but the motive-fluid can be economized, running mostly by expansion with or without the reversers. Without the 5 reversers the cylinder-heads may be dropped very quickly by using springs, but the larger the wheels J² J³ the more rapid the oscillation of cylinder-heads F F, especially if the pins coming in contact with cam D² are very near 10 the axles of wheels J² and J³.

In Fig. 14, I have shown a means of operating the cylinder-heads, without using the system of pulleys and belt or chain, consisting of a central oscillating pulley or disk intermittently operated by the cam D², and connected with the cylinder-heads by means of rods Z Z. Buffers Z² Z³, strike against air-cushions Z' Z' and bring the parts gently to rest after each 15 oscillation.

20 What I claim as my invention and desire to secure by Letters Patent, is:—

1. In a rotary engine, a cylinder-head operated by sprocket-chain and cam-mechanism on the revolving shaft, when running in 25 one direction.

2. A cylinder-head, in a rotary engine, oscillated by sprocket-chain and cam-mechanism on the revolving shaft to run the engine in either direction.

30 3. Two cylinder-heads, each one near the periphery but on opposite extremities of the annular cylinder of a rotary engine, oscillated by sprocket-chain and cam-mechanism on the revolving shaft for running the engine in 35 one direction.

4. Two or more cylinder-heads, in a rotary engine, oscillated by sprocket-chain and cam

mechanism on the revolving shaft for running the engine in either direction.

5. In a rotary engine, a revolving disk bearing adjustable valves admitting motive-fluid alternately through inlets into the annular cylinders of two or more engines. 40

6. In a rotary engine, a casing provided with two annular piston cylinders, a motive-fluid chest intermediate said cylinders, a rotary disk supporting upon its periphery detachable valves for the respective cylinders, and inlet and exhaust ports connected with 45 said cylinders. 50

7. In a rotary engine, a casing provided with two annular piston cylinders, pivoted cylinder-heads engaging at opposite points with the periphery of said cylinders, means connected with the engine shaft for intermittently oscillating said heads, a chamber intermediate said annular cylinders constituting a steam chest, motive-fluid ports connecting said chamber with said cylinder-heads, a rotary disk in said chamber provided with 55 peripheral valves, and disks on either side of said valves provided with openings or channels coöperating with said ports, and means for determining the position of said disks to control the passage of the motive-fluid between 60 said chamber and said cylinders. 65

In testimony whereof I have signed my name to this specification in the presence of two subscribing witnesses.
